UNITED STATES PATENT OFFICE.

EMIL BEROLZHEIMER, OF NEW YORK, N. Y., ASSIGNOR TO EAGLE PENCIL COMPANY, OF NEW YORK, N. Y.

DESIGN FOR A REVOLVING DISPLAY-STAND.

■ No. 39,376.

Specification for Design.

Patented June 23, 1908.

Application filed April 2, 1908. Serial No. 424,830. Term of patent 14 years.

To all whom it may concern:

Be it known that I, EMIL BEROLZHEIMER, a citizen of the United States, residing at New York, county and State of New York, have invented a new, original, and ornamental Design for Revolving Display-Stands, of which the following is a specification, reference being had to the accompanying drawing, forming part thereof.

Figure 1 is a perspective view of the dis-

play stand, Fig. 2 is a plan, and Fig. 3 is a side elevation of the same.

I claim:

The ornamental design for a revolving display stand, as shown.

EMIL BEROLZHEIMER.
